MAILBOX WITH TRANSPARENT AUXILIARY
RECEPTACLE

Carl William Bierig, Joplin, Mo.

Application November 21, 1947, Serial No. 787,343

1 Claim. (Cl. 232—17)

1

The present invention relates to certain new and useful improvements in rural type mailboxes, it being the principal object of the invention to structurally and otherwise improve upon boxes in this field presently known to me.

It is a matter of common knowledge that the rural box customarily used comprises a horizontally elongated sheet metal box having a flat bottom, a dome-like body portion, a vertical fixed rear or back end and a hinged front door, the latter usually mounted to be swung downwardly to permit access to be had to the interior of the box. In addition, these boxes are usually provided on one side with a so-called signalling flag for use both by mail carriers and residents. In order to appreciate the difficulties which attend the use of present-day rural-type boxes, it is perhaps advisable to touch upon matters especially from the viewpoint of the mail carrier. To this end, it is to be kept in mind that in thousands of daily delivery incidents, the rural carrier arrives at a predetermined box in the morning to deliver mail, places mail in the box, and pulls the flag up to show that a delivery has been made. Then, the resident walks out to the box and picks up the mail, but, as a general proposition, fails to pull the flag down, leaving it up, to the confusion of all concerned.

The next day, the rural carrier comes along to the same box, sees the flag up, makes a stop to pick up mail only, for he has no mail to deliver to the box in question, and he finds that the box is empty, that is, is possessed of no outgoing mail. Manifestly, this necessitates a stop for the carrier with a loss of time and wear and tear on his car, and unnecessary consumption of gasoline for stopping and starting.

It is also well, it is believed, to keep in mind the old box referred to and conditions which arise in connection with winter weather, where boxes are snow covered, or covered with ice. Under such delivery conditions, the carrier starts out to deliver mail accompanied by a hammer and a screwdriver, or chisel, as the case may be. Since the type of box now used is designed with an upswinging lid in front, or a lid that hinges at the bottom and swings out and down, under normal temperature conditions, it works satisfactorily, but under bad weather temperatures and conditions, the lid is sealed closed by ice and this necessitates the use of a hammer and a chisel or screwdriver to break the ice loose, and once the box is hammered out of shape and the lid is pried open, said box is thereafter often damaged to the extent that it works unsatisfactorily.

One object of the present invention is to provide a rural-type box whose bottom is provided

2

with a transparent receptacle for outgoing mail, said receptacle being so mounted that it depends well below the bottom of the box so that a portion of the outgoing mail which is situated therein may be seen in the distance by the mail carrier, whereby to notify him that he should stop by and make a pickup of mail.

Another object is to provide a box having an outgoing transparent mail depository or receptacle which is substantially water and freeze-proofed.

A further object of the invention is to provide a rural-type box having a corrugated bottom for reception of mail left by the carrier to be picked up by residents, this being preferable, in that it prevents the mail from adhering or sticking to the bottom and, in so doing, facilitates removal of same.

Another object of the invention is to provide 20 a box having a relatively stationary or fixed bottom and a shell-like body portion, the latter having both front and rear ends fixedly mounted, the rear end of said body being hingedly mounted on the bottom and the entire box or body being 25 swung up and away from the bottom to facilitate inserting and removing mail and also to insure protection of same under all weather conditions.

Other objects, features and advantages will become more readily apparent from the following 30 description and the accompanying illustrative drawings.

In the drawings wherein like numerals are employed to designate like parts throughout the views:

35 Figure 1 is a perspective view of a rural-type mail delivery box constructed in accordance with the principles of the present invention;

Figure 2 is a horizontal section on the plane of the line 2—2 of Figure 1, looking in the direction 40 of the arrows;

Figure 3 is a central vertical sectional view on the line 3—3 of Figure 2, looking in the direction of the arrows; and

Figure 4 is a cross section on the transverse 45 line 4—4 of Figure 3, also looking in the direction of the arrows.

Referring now to the drawings by distinguishing reference numerals, attention is directed first to Figures 1 and 3 wherein the rigid support is 50 in the form of a post or the like 6 and the box proper is denoted by the numeral 7. The latter, instead of being formed with a solid bottom and body included, is made up of two sections or relatively movable parts. That is to say, the box proper is in the form of a hood-like shell which 55 includes a hood or dome portion 8, a vertical fixed rear closing end 9, and a corresponding vertically

fixed front closing end 10, the latter having a suitable and properly exposed hand grip 10a. The bottom, which is a separate part, is denoted by the numeral 11 and is a horizontal corrugated plate having a fixedly attached collar 12 screwed on the upper screw-threaded end of the supporting post 8; as shown in Figure 3. The bottom has longitudinal upstanding walls 13 which coact with the bottom in forming a sort of trough-like receiver for mail which is left by the carrier to be picked up by the house residents. The numeral 13 designates an appropriately constructed arcuate brace which is fastened at 14 to the post and secured at its opposite end to the forward portion of the corrugated bottom 11. The lower skirt-forming portion of the box surrounds the bottom and flanges, as shown in Figure 3. What is more, the rear end portion of the box is mounted on a hinging axle or pin 15; the latter being seated in bearings 16, as shown in Figure 1. Coiled springs 17 (see Figure 2) surround the end portions of the axle on the interior of the box and are connected together by a detent 18 which rests against the fixed bottom 11. The end portions of the convolutions or coils are attached to rigidly attached anchoring hooks 19 on the interior of the vertical side walls of the box proper. The spring means, acting on the box and bottom and axle, serves to automatically swing the box up to the dotted line or open position illustrated in Figure 4. Retaining means is provided to normally hold the box in a down or closed position. This means comprises an adapter 20 which is carried on the under side of the forward end portion of the bottom 11 and which serves to accommodate a rocker shaft 21. The rocker shaft is properly mounted in bearings for rotational purposes and one end portion projects and is provided with a hand grip 22. The rocker shaft is provided with a latch finger 23 having a hook 24 to engage a keeper 25 on the inside of the front wall of the box 7, as shown in Figure 3. The spring members 26 and 27 are mounted in the adapter and coact with the rocker shaft and latch finger to hold the finger normally pressed into latching position. By catching hold of the hand grip 22 and rocking the shaft 21 against the spring tension set up by the spring means referred to, it is obvious that the box is then released and the spring means 17 and 18 previously referred to comes into play to automatically swing the entire box up to open, inclined position. It follows that when the mail carrier comes along and desires to deposit the mail in the box, he simply catches hold of the handle 22, rocks the shaft 21, releases the latch, and the box goes up to expose the corrugated trough portion for reception of mail to be picked up by residents.

Attention is now directed to the most important aspect of the invention. This has to do with a novel weather-proofed depository or receptacle which is built into and forms a part of the box and which is situated and satisfactory to accommodate outgoing mail. This depository or means is referred to generally by the numeral 28 and comprises a transparent receiver. Actually the receiver is made up of a suitable metal or equivalent frame 29 of rectangular form and this is in the nature of a hanger and is suspended in the apertured portion of the bottom 11, as shown in Figure 3. The frame serves to accommodate and hold a pair of insertable and removable glass or equivalent panels or panes 30. These panes, in conjunction with the bottom of the box and the framework, make up a substantially rectangular

pocket-like depository. This depository opens into the box proper and serves to accommodate outgoing mail, as denoted by the numeral 31. By opening the box, the resident deposits mail which is to be mailed out, this in the depository 28. As the depository depends to an elevation below the under side of the bottom, and as the windows or panels are transparent, it is obvious that the mail carrier driving by will see the mail resting in the depository and will, regardless of the position of the flag (not shown), stop by and make the necessary pickup. It is obvious that the means 28 is for outgoing mail and that the corrugated bottom is used for incoming mail.

Taking into consideration all of the perplexing difficulties met by both carriers and residents in reference to rural mail delivery service, it is obvious that considerable time could be spent here dwelling upon various factors in relation to same. It is clear, however, that I have touched upon only the principal difficulties and have stressed the details of construction which go to make up the improved box and the various phases thereof. Such a disclosure appears to be adequate for my purposes.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claim.

Having described the invention, what is claimed as new is:

In a rural-type mailbox, a box proper, said box being constructed to permit access to be had to the interior and including a stationary bottom, said bottom being provided centrally with a longitudinal mail slot, a frame attached to and depending rigidly from the underside of said bottom in alignment with said mail slot, and spaced parallel glass panels mounted in said frame, said frame, glass panels and bottom being interconnected in weathertight relationship to provide a receiver for outgoing mail, whereby mail placed in said receiver by way of said box may be clearly seen, from both sides of the receiver, by a mail carrier at a relatively distant point.
